(57) **CLAIM**

The ornamental design for a glue pen, as shown and described.

DESCRIPTION

FIG. 1 is a perspective view of a glue pen showing my new design;

FIG. 2 is another perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

Certain nozzle portions, cord portions, button actuator portions, rivet portions and contour transition line portions have been reduced to broken lines.

The broken lines in the drawing views are included for the purpose of illustrating unclaimed environment only, and form no part of the claimed design.
